UNITED STATES PATENT OFFICE.

DANIEL F. SULLIVAN, OF LOWELL, MASSACHUSETTS, ASSIGNOR OF ONE-HALF TO GEORGE F. BLAIR, OF SAME PLACE.

CIRCULAR SPRING-NEEDLE KNITTING MACHINE.

SPECIFICATION forming part of Letters Patent No. 431,292, dated July 1, 1890.

Application filed December 20, 1889. Serial No. 334,396. (No model.)

To all whom it may concern:

Be it known that I, DANIEL F. SULLIVAN, a citizen of the United States, residing at Lowell, in the county of Middlesex and Commonwealth of Massachusetts, have invented a certain new and useful Improvement in Circular Spring-Needle Knitting Machines, of which the following is a specification.

My invention relates to circular spring-needle knitting machines, its object being to knit "mock-rib" or "drop-stitch" or vertical stripes for a certain distance, and then to knit plain work; and my invention consists in the combination of long-bearded needles, alternating with a series of short-bearded needles, with a loop-wheel, and means of holding said loop-wheel at such a height as to carry the yarn under the beards of all said needles or at will at such a height as to carry the yarn under the beards of the short-bearded needles only; and it consists, also, in other devices and combinations hereinafter described and claimed.

In the accompanying drawings, Figure 1 is an isometric perspective view of so much of a circular spring-needle knitting machine as is necessary to illustrate my invention with my improvement applied thereto. Fig. 2 is a central section in the plane of the axis of the 30 loop-wheel stud of the upper horizontal part of a loop-wheel stand to which my improvement is applied, showing also the loop-wheel in central section in its lower position, showing also in side elevation a long-bearded and 35 a short-bearded needle. Fig. 3 is like Fig. 2, except that the loop-wheel is in its higher position, my improvement being shown in Figs. 2 and 3 as adapted to be operated by hand, while in Fig. 1 automatic means of operating 40 said improvement are shown; Figs. 4 and 5, projections of a part of the head and a row of short and long bearded needles and a line representing a yarn, which in Fig. 4 runs below the beards of all the needles and in Fig. 45 runs below the beards of the short-bearded needles only.

The supporting bed or table A, the needle-cylinder B, carrying needles C C', the adjustable loop-wheel stand or star-box D, and 50 the loop-wheel E are all of the usual construc-

tion and operation, except as hereinafter described.

Usually all the needles in the same cylinder have beards of uniform length; but this is not always the case. In Figs. 1, 4, and 5 a series of four short-bearded needles is represented as alternating with single long-bearded needles. The loop-wheel E makes stitches or loops by pressing the yarn between the shanks of the needles and below the beards of the same, and unless the yarn falls below the beard of any needle no stitch will be formed by that needle. The loop-wheel E, when in its lower or normal position, carries the yarn under the beards of all the needles and forms as many loops in a course or in one revolution of the needle-cylinder as there are needles both long-bearded and short-bearded in said cylinder; but if the loop-wheel is slightly raised, as by the means hereinafter described or otherwise, so as to carry the yarn over the beards of the long-bearded needles and under the beards of the short-bearded needles, no stitch will be formed by the long-bearded needles, and there will be as many "drop-strokes" or "mock-rib," so called, as there are long-bearded needles in the cylinder. It is frequently desirable to knit the legs or the upper portions of the same of hosiery with mock-rib and to knit the lower part of the leg and foot plain.

The means I adopt for changing from ribbed work to plain consists of a piece F, which, from its office, I call a "lifter," the same being a piece of metal, the inner edge of which is beveled or wedge-shaped and may be crowded under the hub of the loop-wheel E to raise said wheel on its stud e. As represented, the piece F is L-shaped in section, its horizontal part resting upon the loop-wheel stand and its vertical part being secured to a rod G, which runs through a hole concentric with the axis of the spindle e' or radially-adjustable portions of the loop-wheel stand. The outer end of the rod G may be provided with a button or knob H, adapted to be grasped by the fingers to push said rod inward toward the loop-wheel or to draw it outward from said loop-wheel. When the rod G is pushed inward into the position shown in

Fig. 3, the lower part of the piece F is crowded under the hub of the loop-wheel and raises it slightly, enough to cause the loop-wheel to carry the yarn above the lower end of the 5 beards of the long-bearded needles C', as shown in Fig. 5; but when the rod is drawn outward or away from the loop-wheel and the loop-wheel rests in its usual position upon the spindle of the loop-wheel stand, the loop- 10 wheel carries the yarn below the beards of all the needles and knits plain work.

It is not absolutely essential that the yarn-guide I, which is provided with a yarn-eye i, and is commonly fixed on the loop-wheel stand 15 at a certain height relatively to the height of the loop-wheel, should be raised and lowered when the change is made from plain work to ribbed work, or vice versa; but it is better that the yarn-eye i should be so raised, especially 20 where the beards of the needles vary greatly in length. I therefore preferably provide the piece F with a laterally-extending arm or pin f, which reaches through an inclined slot i' in the yarn-guide, and I pivot 25 the yarn-guide on a stud or screw passing through the outer end of said guide into the loop-wheel stand, the inclination of said slot i' being such that the longitudinal movement of the rod G and the arm f raises the yarn i 30 at the same time the loop-wheel is raised and to an equal amount.

In Fig. 1 automatic means are shown for imparting a longitudinal movement to the rod G. The outer end of the rod G in Fig. 1 35 is provided with a collar K, having an annular groove k to receive the forked upper end l of a lever L, pivoted at its lower end l' on a bracket l'', secured to the bed A, and a leaf-spring M is secured to said bracket and 40 presses upon the lever L above its fulcrum and normally presses said lever and the rod G inward to hold the loop-wheel in a raised position. The lever L is provided with a stud l'', which projects inward toward the needle-cylinder and bears upon the periphery of a 45 cam-wheel N, journaled upon a bracket n, secured to the bed A. The cam-wheel N is represented as having a periphery consisting of two oppositely-arranged arcs n' of equal 50 radius and having an angular measurement of ninety degrees each, and two other arcs n'' of a greater radius. The wheel N is provided with an internally-toothed annular ratchet n'', engaged by a pawl o, pivoted at o' to the 55 ratchet-lever O and held in engagement with said ratchet by a spring o'', secured to said lever O and pressing upon said pawl. The lever O is pivoted at o'' upon the loop-wheel stand, and its inner end, or end next the needle-cylinder, is drawn down by a spring o', connecting the inner arm of said lever and the bed A. The needle-cylinder B is provided with a cam b, which once in every revolution of said cylinder strikes and throws upward 60 the inner end of the lever O and causes the pawl at the outer end of said lever to ro-

tate the cam-wheel N an angular distance represented by one tooth of the ratchet n'', so that in a number of revolutions of the needle-cylinder equal to the number of teeth in said ratchet the cam-wheel N will make a complete rotation. The difference of radius of the arcs n' on the one hand and the arcs n'' on the other hand is sufficient to vary the position of the lever L and rod G enough to 70 raise the loop-wheel to its highest position when the arcs n' are in contact with the stud l'', and to allow the loop-wheel to fall when the arcs n'' are in contact with such stud.

Obviously another loop-wheel, as shown at 80 E' in Fig. 1 in dotted lines, may be used, said last-named wheel running at a fixed height and low enough to carry the yarn under the beards of all the needles. If such an additional loop-wheel be used and yarns of different colors be introduced into the machine—one color by each loop-wheel—the groundwork of the fabric will show a mixture of these colors; but only the color introduced by the wheel E' will show on the long-bearded 85 needles—that is, the fabric will have vertical stripes of the color carried by said last-named loop-wheel. Obviously the width of the stripes of pure color will depend on the number of adjacent long-bearded needles. It is undesirable to use too many adjacent long-bearded 90 needles in connection with the improvement above described, because the yarn carried by the loop-wheel E floats on the wrong side of the fabric where the stripes of pure color come, 100 such stripes of pure color appearing only on the face of the fabric by "floats" meaning yarns which are not incorporated into the body of the fabric.

I claim as my invention—

105

1. The combination of the needle-cylinder, long-bearded needles alternating with series of short-bearded needles, a loop-wheel normally carrying its yarn under the beards of all said needles, and means of raising said loop-wheel to carry said yarn under the beards of said short-bearded needles only, as and for the purpose specified.

2. The combination of the needle-cylinder, a series of needles arranged therein, a part of 115 said needles having longer beards than the rest thereof, a loop-wheel normally carrying its yarn under the beards of all of said needles, and a lifter to raise said loop-wheel and to carry its yarn under the beards of the 120 short-bearded needles only, as and for the purpose specified.

3. The combination of the needle-cylinder, short-bearded needles and long-bearded needles, the loop-wheel, a lifter arranged below 125 said wheel, a loop-wheel stand supporting said wheel and lifter, a rod secured to said lifter and extending horizontally through a hole with which said loop-wheel stand is provided to enable said loop-wheel stand to be raised 130 and lowered by the movement of said rod to cause the yarn carried by said loop-wheel to

be introduced under the beards of all of said needles or under the beards of the short-bearded needles only, as and for the purpose specified.

- 5 4. The combination of the needle-cylinder, long-bearded needles and short-bearded needles, the loop-wheel stand, the loop-wheel supported thereon, the lifter adapted to be pushed under said loop-wheel to raise the same and having a laterally-projecting pin, a yarn-guide pivoted on said loop-wheel stand and having a yarn-eye and also having an inclined slot to receive said projecting pin, whereby the movement of said lifter will vary the height of said loop-wheel and yarn-eye relatively to the beards of said needles without changing the height of said loop-wheel and yarn-eye relatively to each other, as and for the purpose specified.
- 10 5. The combination of the needle-cylinder provided with long-bearded needles and with short-bearded needles, the loop-wheel stand, the loop-wheel supported thereon, a lifter adapted to be moved under said loop-wheel to raise the same, and automatic means, substantially as described, of moving said lifter at the completion of a given number of revolutions of said needle-cylinder, as and for the purpose specified.

6. The combination of the needle-cylinder 30 having long-bearded needles and short-bearded needles, the loop-wheel stand, the loop-wheel supported thereon, the lifter arranged to slide upon said stand under said loop-wheel and out from under the same, a rod secured 35 to said lifter and arranged to slide in a horizontal hole with which said loop-wheel stand is provided, said rod having a collar, the bed, the lever pivoted on said bed and provided at its upper end with a fork to engage said collar, a spring to press upon said lever and to push said lifter under said loop-wheel, said lever being provided with a stud, a cam-wheel having a cam-surface bearing against said stud and having also a ratchet, a ratchet-operating lever having a pawl to engage said ratchet, a cam on said needle-cylinder arranged to operate said ratchet-operating lever in one direction, and another spring to operate said ratchet-operating lever in the other 40 45 50 direction, as and for the purpose specified.

In witness whereof I have signed this specification, in the presence of two attesting witnesses, this 23d day of November, A. D. 1889.
